Patented Oct. 10, 1922.

UNITED STATES PATENT OFFICE.

CALVIN H. LUCY, OF BALTIMORE, MARYLAND, ASSIGNOR TO THE SINGER MANUFACTURING COMPANY, A CORPORATION OF NEW JERSEY.

WORK HOLDER FOR SEWING MACHINES.

Application filed October 18, 1917. Serial No. 197,175.

To all whom it may concern:

Be it known that I, CALVIN H. LUCY, a citizen of the United States, residing at Baltimore, in the State of Maryland, have invented certain new and useful Improvements in Work Holders for Sewing Machines, of which the following is a specification, reference being had therein to the accompanying drawings.

10 This invention relates to sewing machines, more particularly of the type adapted to lay groups of tacking stitches in predetermined order or arrangement to form an ornamental design, and has for an object to provide a 15 work-holder for use with such machines, whereby the work may be turned about a given center between stitching cycles to relocate the work relatively to the stitch-forming mechanism for reception of subsequent 20 groups of stitches displaced angularly about said center from previously formed groups.

More specifically the invention has for an object to provide a special work-holder for "fern-leaf tacking" machines, whereby the 25 work may be so rotated and the successively formed groups of stitches or "fern-leaf tacks" so laid as to produce ornamental star-shaped figures having any desired number of points.

30 The invention is preferably embodied in a machine of the well known Singer button sewer type disclosed for example in the patent to J. J. Sullivan, No. 777,564, and comprising a reciprocating needle operating 35 in conjunction with the work-holder to which predetermined lateral jogging movements are imparted by means of a suitable pattern-cam. The machine is provided with the usual stop-motion device and tripping 40 means therefor arranged to operate the stop-motion device to arrest the stitch-forming mechanism at the end of each stitching cycle, that is, at the completion of each 45 group of tacking stitches, so as to permit the work to be relocated relatively to the stitch-forming mechanism for reception of subsequent groups of tacking stitches.

In the present instance the work-holder 50 comprises a pair of opposed clamping rings the lower of which is journaled to turn in the lower or base member of the work-holder and the upper of which is journaled to turn

in the overhanging or presser-member of the work-holder. The opposed faces of the clamping rings are serrated or formed with 55 work-gripping teeth and manually controlled means are provided for turning the upper ring to the desired extent in its support while the work is securely gripped; the lower ring being free to turn with the work, 60 In the present machine the work-holder controlling cams are cut so as to shift the work-holder for reception of stitches grouped to produce the well known fern-leaf shaped ornament and by means of the rotatable 65 work-holder the work may be accurately turned one-fifth of a revolution, say, between each stitching operation, thus effecting production of a five pointed star; the points of the fern-leaf ornaments radiating 70 from a common center and the base-portions being superimposed more or less to fully conceal the body-fabric and add to the thickness and ornamental appearance of the center of the composite ornament. 75

In the accompanying drawings, Fig. 1 is a side elevation of a machine embodying the invention. Fig. 2 is a perspective view of the work-holder. Fig. 3 is a perspective view showing the well known cam-controlled 80 connection for imparting longitudinal components of motion to the work-holder. Fig. 4 is a cross-section of the work-holder. Figs. 5, 6 and 7 are detailed perspective views of parts of the work-holder. Fig. 8 illustrates 85 a five pointed star as produced by the present machine; one of the points of the star being shown incomplete to indicate the direction in which the stitching progresses. Fig. 9 illustrates the so-called "fern-leaf 90 tack" or group of stitches produced during one stitching cycle by the particular machine in which the invention is at present embodied.

The particular machine in which the invention is shown as embodied is constructed substantially in accordance with the disclosure in the said Sullivan patent or in the patent to Barron, No. 1,093,241 and comprises the bed 1, standard 2 and bracket-arm 3 terminating in a head 4 in which is journaled the reciprocating needle-bar 5 carrying the eye-pointed needle 6 cooperating preferably with the usual oscillating shuttle 95 100

(not shown). The needle-bar is reciprocated by means of the usual crank and link connection with the rotary main-shaft 7 having upon its rearward end the tight and loose 5 pulleys 8 and 9, respectively, the former having secured thereto the usual stopping cam 10.

In the present instance the work-holder is carried by the slide-bar 11 to the rearward 10 end of which is secured the vertical post 12 which enters the slotted lower arm 13 of the usual rock-lever fulcrumed in a rigid bracket 14. The upper arm 15 of the rock-lever carries a cam-follower or roller-stud 16 which 15 enters the cam-groove 17 of the pattern-wheel 18.

The slide-bar 11 is vibrated laterally about the post 12 as a fulcrum by means of the usual connections including the slide-plate 20 19 which is shifted laterally by means of the bellcrank-lever 20 receiving motion from the link 21 and rock-lever 22, the upper end of which carries a cam-follower 23 entering the cam-groove 24 in the outer face of the 25 pattern-wheel 18.

It will be readily understood that the cam-grooves 17 and 24 in the pattern-wheel may be designed to shift the work-holder in any direction and to any desired extent (within 30 limits) between penetrations of the needle 6, so that the stitches may be laid in any desired order or arrangement. In the present instance these cam-grooves are shaped to jog the work-holder to secure an arrangement or grouping of stitches simulating a fern-leaf, as shown in Fig. 9.

The machine is preferably equipped with the usual stop-mechanism including the stop-motion lever 25 which is held in running 40 position by the latch 26 adapted to be tripped by the tripping point 27 carried by the cam-wheel 18, as more fully described in said Barron patent.

The present work-holder, in its preferred 45 embodiment, comprises a lower work-support or work-supporting ring 28 having a flat under surface 29 adapted to rest upon and slide freely over the upper surface of the usual throat-plate 30 in which is formed a needle-hole 30'. The ring 28 is journaled to turn in a guide-ring 31 formed with a shank 32 bolted to the forward end of the slide-bar 11 and is confined against upward displacement relatively to said guide-ring 50 by means of the inwardly directed annular flange 33 formed on said guide-ring and overlapping the lower outwardly directed annular flange 34 formed upon the work-supporting ring 28. The ring 28 is beveled 55 at 35 to form a conical work-supporting surface which is provided with upwardly directed work-gripping serrations or teeth, as illustrated. Cooperating with the work-supporting ring 28 is a presser or work-clamping ring 36 having a serrated conical

work-gripping surface 37 registering with the conical work-supporting surface 35. The presser-ring 36 is formed with a thickened hub 38 and with a thin outwardly projecting annular flange 39 having a thickened base-portion 40 upon which rests the ratchet-ring 41 having at its outer periphery ratchet-teeth 42 and notched at 43 to embrace a key 44 fixed to the hub 38 of the presser-ring 36. Fulcrumed in the bearing 75 afforded by the opposed faces of the flange 39 and ratchet-ring 41 is the ring-shaped inner end of the hand-lever 45 the outer end of which is formed with an up-turned lip 46 affording a handle or finger-piece. The 80 hand-lever carries a pawl 47 which is pressed against the ratchet-teeth 42 by means of the spring 48.

Screwed to the upwardly extending end of the hub 38 of the presser-ring 36 is the 85 flat retaining ring 49 between which and the ratchet-ring 41 a space is afforded to receive the presser-support or supporting ring 50 having diametrically opposed upturned ears 51 apertured to loosely embrace the pivotal screws 52 which are threaded into the forwardly extended lower extremities of the presser-bars 53 mounted side-by-side for vertical sliding movements in the head 54 of the clamp bracket-arm 55 which is secured to the slide-bar 11. Bearing downwardly upon the notched upper ends of the presser-bars 53 are the springs 54' whose rearwardly disposed extremities rest upon the support 56 carried by the clamp bracket-arm 55 and the pressure of which may be adjusted by means of suitable adjusting screws, one of which is shown at 57.

In the present instance one face of the retaining ring 49 is provided with five uniformly spaced radial grooves 58 while the opposite face is provided with three radial grooves 58' spaced 120° from one another. The down-turned forward extremity of the spring 59 secured to one of the presser-bars by a screw 59' is adapted to bear upon the exposed surface of the ring 49 and snap into a radial groove to yieldingly retain the presser-ring 36 in the desired predetermined position to which it is shifted by manipulation of the hand-lever 45. When it is desired to stitch a five pointed star for example, the retaining-ring 49 is secured to the hub 38 with the five grooves 58 uppermost. When it is desired to stitch a three pointed star, the ring 49 is reversed so as to expose the three grooves 58' to the detaining action of the spring 59. Obviously additional rings 49 having variously spaced grooves may be provided for use in lieu of the particular retaining ring shown.

In order that the presser-ring may be lifted to release the work the presser-bars 53 are provided with forwardly projecting lateral pins 60 which overhang the lateral 130

clamp-lifting bar 61 secured to the lower end of the vertical slide-bar 62 journaled in the head 4 and at its upper end connected to the usual treadle-controlled clamp-lifting lever 63.

It is desirable to provide the machine with means for stripping the work from the needle. In the present instance the needle is surrounded by a stripper ring 64 whose shank 65 is slidably received within a socket in the needle-clamp block 66. A screw 67 passing through a slot 68 in the needle-clamp block and threaded into the shank 65 prevents turning movements of the latter. The expansion spring 69 surrounding the reduced upper end portion of the shank 65 depresses the stripper ring 64 during the first part of the up-stroke of the needle to hold the fabric against the throat-plate so that the needle will be certain to throw out its loop.

In the operation of the machine the presser-ring 36 is lifted by manipulation of the lever 63 and the work is placed in a desired position over the work-supporting ring 28. Upon lowering the presser-ring the work will be securely gripped between the coacting conical gripping surfaces 37 and 35; the independently yielding presser-bars 53 and free pivotal connections 52 permitting the presser-ring to tilt slightly in any direction in adjusting itself to possible inequalities in the thickness of the work at hand.

With the work firmly clamped in place the stitch-forming mechanism is caused to run through the usual stitching cycle to form a group of tacking stitches such as the star-point shown in Fig. 9, and come to a stop. It will be seen that each group of stitches forming an elementary figure is symmetrically laid along a line radiating from the center of the work-holder. The operator, without releasing the work, moves the handle 45 to rotate the presser-ring the desired number of degrees or until the spring 59 snaps into the succeeding radial groove in the retaining ring 49, thereby bringing another portion of the work into the line of stitching whereupon the machine is started and, in the present instance, another point of the star is made. The work is thus alternately shifted and stitched until the star is completed, as will be readily understood.

The machine is thus capable of stitching a composite figure made up of a series of elementary figures repeated at intervals spaced angularly about a given center. The work-holder may obviously be turned any desired number of degrees between stitching operations; the grooves 58 or 58' merely aiding in positioning the work-holder to secure the production of a composite figure comprising accurately spaced elementary figures.

While the present improvement is shown as embodied in a machine of the jogging

work-clamp type it is evidently adapted for use in tacking or embroidering machines of other types and is susceptible of material modification in the construction and arrangement of its parts within the scope of the invention.

Having thus set forth the nature of the invention, what I claim herein is:—

1. In a sewing machine, in combination stitch-forming mechanism including a reciprocating needle, a work-holder, means for producing automatically variable relative bodily lateral movement having two components between said stitch-forming mechanism and work-holder to produce a stitch covered elementary figure, and means for imparting movements of rotation to said work-holder between elementary figure stitching operations. 75

2. In a sewing machine, in combination, stitch-forming mechanism, a work-holder, means for producing relative lateral movement between said stitch-forming mechanism and the work-holder to effect the stitching of a single covered star-point, means for stopping the stitch-forming mechanism at the close of the operation and means for relatively rotating said work-holder and stitch-forming mechanism about a given center while such stitch-forming mechanism is 90 ineffective to accurately relocate the work relatively to said center for reception of subsequent starpoints. 95

3. In a sewing machine, in combination, stitch-forming mechanism including a reciprocating needle, a rotary work-holder, means for securing said work-holder against rotation in any one of a plurality of predetermined positions during a stitching operation, means for producing relative lateral 100 movement between said stitch-forming mechanism and work-holder in the production of an elementary figure, and means for imparting movements of rotation to said work-holder between elementary figure 105 stitching operations. 110

4. In a sewing machine, in combination, stitch-forming mechanism including a reciprocating needle, a work-holder, means for producing automatically variable relative 115 bodily lateral movement having components in transverse directions between said stitch-forming mechanism and work-holder in the production of an elementary stitch covered figure, and manually operated means for imparting movements of rotation to said work-holder between elementary figure stitching operations. 120

5. In a sewing machine, in combination, stitch-forming mechanism including a reciprocating needle, a work-holder movable in directions transverse to each other and including a work-support and a rotatably mounted presser-member for clamping the work against said work-support, means for 125 130

producing predetermined relative lateral movements between said stitch-forming mechanism and the work-holder in the production of an elementary figure, means occupying a normally fixed relation to said work-holder during the action of the stitch-forming mechanism for imparting the movement of rotation to said work-holder while the stitch-forming mechanism is inactive, and means for determining stopping places in the rotary movement of the work-holder.

6. In a sewing machine, in combination, a stitch-forming mechanism including a reciprocating needle, a stop-motion device, a work-holder including a work-gripping element adapted to present the work to said needle substantially in a plane, means for imparting components of motion to said work-holder in mutually transverse directions laterally of said needle to produce a desired elementary stitched figure, and manually operated means for turning said work-gripping element in a plane substantially parallel to the plane of the work while the stitch-forming mechanism is inactive.

7. A work-holder for sewing machines comprising, in combination, a work-support, a presser-support, a presser-member mounted in said presser-support to turn in a plane substantially parallel to the plane of the work, and a universal yielding connection between said supports, whereby said presser-member may tilt slightly in any direction in adapting itself to inequalities in the work's thickness.

8. A work-holder for sewing machines comprising, in combination, a work-support, a presser-support, a presser-member mounted in said presser-support to turn in a plane substantially parallel to the plane of the work, a universal yielding connection between said supports, whereby said presser-member may tilt slightly in any direction in adapting itself to inequalities in the work's thickness, and means for lifting said presser-member to release the work.

9. A work-holder for sewing machines comprising, a work-support, a plurality of independently spring-pressed presser-bars, a presser-ring support, a presser-ring rotatably mounted in said support, and pivotal connections between said support and said presser-bars, said pivotal connections being arranged substantially diametrically of said presser-ring.

10. A work-holder for sewing machines comprising, a throat-plate, a work-supporting ring having a flat under-surface adapted to slide upon said throat-plate, a guide-ring in which said work supporting ring is mounted to turn, a presser-ring adapted to clamp the work against said work-supporting ring, and manually controlled means for turning one of said rings.

65 11. A work-holder for sewing machines

comprising complementary work-gripping rings, means for imparting movement to the work-holder in transverse directions, means for imparting a succession of partial rotations to said rings, and reversible means for variably determining the extent of such partial rotation.

12. In a sewing machine, stitch-forming mechanism, a work-holder, automatic means for producing relative stitch-positioning movements between the stitch-forming mechanism and the work-holder to produce an elementary stitch covered figure, an automatic stop-motion device for arresting the stitch-forming mechanism at the completion of each elementary stitch covered figure, and means for producing relative turning movements between the work and stitch-forming mechanism while the latter is at rest, whereby a series of such figures may be symmetrically laid about a given point.

13. In a sewing machine, stitch-forming mechanism, a work-holder, means for laying stitches on the work transversely to and at each side of a line radiating from the center of the work-holder to form a stitch-covered figure, and means for relatively shifting the work and stitch-forming mechanism either a predetermined or an arbitrary amount and means whereby the work may be held in any one of a plurality of predetermined positions.

14. In a sewing machine, a stitch-forming mechanism and a work-holder having a plurality of predetermined relative movements, yielding means for securing the parts against one of said movements while others are in progress, means for producing the latter movements, and means for producing said first movement at will against the opposition of said yielding means.

105 15. In a sewing machine, stitch-forming mechanism, a work-holder, means for producing a series of stitch covered star points in separate automatically controlled operations, means whereby the work-holder may be moved between operations, and means for accurately gaging the extent of such movements.

16. In a sewing machine, stitch-forming mechanism, a work-holder, means for producing in separate automatically controlled operations a series of radially extending stitch covered figures at the center of the work-holder, means whereby the work-holder may be rotated between operations, and means for accurately gaging the extent of such rotation.

115 17. In a sewing machine, stitch-forming mechanism, a work-holder, automatic means acting independently of the work for relatively moving the stitch-forming mechanism and the work-holder to produce an elementary stitch-covered figure, and means for producing relative shifting movements between the work and the stitch-forming

mechanism whereby a series of such figures may be symmetrically laid about a given point.

18. In a sewing machine, stitch-forming mechanism, a work-holder, automatic means for causing relative movement between the work-holder and the stitch-forming mechanism to produce an elementary stitch-covered figure, and separate means for pro-

ducing relative movement between the work-holder and stitch-forming mechanism at the completion of each elementary figure, whereby a series of such figures may be laid about a given point.

In testimony whereof, I have signed my name to this specification.

CALVIN H. LUCY.
